UNITED STATES PATENT OFFICE

WILLIAM HALES, OF ST. LOUIS, MISSOURI, ASSIGNOR TO CHARTER OAK STOVE AND RANGE COMPANY, A CORPORATION OF MISSOURI.

SNAP-BAND FOR MOLDS.

No. 896,379.

Specification of Letters Patent.

Patented Aug. 18, 1908.

Application filed April 20, 1908. Serial No. 428,039.

To all whom it may concern:

Be it known that I, WILLIAM HALES, a citizen of the United States, and resident of St. Louis, Missouri, have invented certain new and useful Improvements in Snap-Bands for Molds, of which the following is a specification.

This invention relates to improvements in snap bands for molds, and consists in the novel arrangement, construction and combination of parts as will be fully hereinafter described and claimed.

The object of my invention is to construct a band which is designed to fit over a sand mold, after the snap flask in which the mold has been formed has been removed, preparatory to pouring the molten metal into the mold.

A further object of my invention is to place my improved band over the mold preparatory to the pouring of the molten metal into the mold for completely covering the joining edges of the mold preventing the leakage of metal which might by chance pass through the center joint located between both halves of the mold.

Figure 1 is a perspective view of a mold which has been formed in an ordinary wooden snap flask. Fig. 2 is a perspective view of the same with the snap flask removed and the mold in its formed position. Fig. 3 is a central sectional view of the mold with my invention in the act of being applied thereon. Fig. 4 is a similar view to Fig. 3 showing my improved band in position. Fig. 5 is a perspective view of my improved snap band.

In the construction of my invention, I provide a band made preferably of a strip of sheet steel 6, bent at the point indicated by the numeral 7 forming sharp corners; the one end 8 of the strip is securely fastened to the opposite end by riveting the same together. The edges of the strip of sheet metal are bent at right angles forming flanges 9 and 10, the said flanges being slit where the strip is bent forming the corners and are turned inwardly forming the loops 11. The object of this is to avoid sharp edges so as to prevent cutting the hands of the person holding the same.

The object of the flanges 9 and 10 is to

stiffen the band as well as acting for handles, and the corners 12 when bent are sufficiently rounded so as to smooth the sides of the sand mold when the band is being placed over the mold, and as the said band is being placed in position, the recess 13 which is generally formed by the result of the placing of the upper and lower sections of the mold in position, is filled with the surplus sand making a complete joint as shown in Fig. 4 when the band is in its operative position. This will prevent the molten metal which is poured through the gate 14 from seeping through the joining edge 15 and contacting with the sides of the band.

Heretofore, wooden bands have been used and the inner surface of the bands have been burned by the molten metal which on occasions passed through the joining edge 15. The essential feature of my invention is to dispense with this difficulty as well as to prevent the warping of such bands by the varying temperature of the sand of which the molds are formed.

A band of this construction is more durable than the wooden bands, more rigid, has a better binding quality, lighter, and more convenient to handle.

Having fully described my invention, what I claim is:

1. A snap band for molds comprising a frame composed of walls formed of a single strip of sheet material; the edges bent outwardly forming flanges; the corners of said flanges bent inwardly; substantially as specified.

2. A device of the class described comprising a strip of sheet material suitably bent forming a frame; the ends rigidly secured together; flanges formed by bending the edges of the sheet material acting as stiffening members as well as handles; the corners of said flanges being bent under; said device being adapted to be placed over the sand mold to bind the same while the molten metal is being poured into the mold, substantially as specified.

3. A snap band for molds comprising a frame of sheet material formed of a single strip so arranged as to be placed over a mold

after the cope and drag has been removed from the mold for supporting the mold while the molten metal is being poured therein, flanges formed by bending the upper and 5 lower edges of the strip, the corners of said flanges slit and bent under so as to avoid sharp edges, substantially as specified.

In testimony whereof, I have signed my name to this specification, in presence of two subscribing witnesses.

WILLIAM HALES.
